UNITED STATES PATENT OF

EDWARD A. SCHREIBER, OF CHICAGO, ILLINOIS, ASSIGNOR TO EGBI
CHICAGO, ILLINOIS.

VESTIBULE-DIAPHRAGM FOR RAILWAY-CARS.

1.171.259.

Specification of Letters Patent.

Patente

Application filed November 24, 1914. Serial No. 873,766.

To all whom it may concern:

the face plate of the diap

Be it known that I, EDWARD,
a citizen of the United States,

5 a citizen of the United States, residing at Chicago, in the county of Cook and State of Illinois, have invented certain new and useful Improvements in Vestibule-Diaphragms for Railway-Cars, of which the following is a specification.

My invention relates to a vestibule dia-
10 phragm for railway cars, and has for its
principal object to provide a vestibule dia-
phragm which may be made entirely of
metal and which will be simpler and more
economical in construction and more dura-
15 ble than the leather diaphragm in use at the
present time, or the various substitutes for
the same which have been heretofore pro-
posed and experimented with to a certain
extent.

20 A further object of the invention is to provide an all metal vestibule diaphragm which will be light in weight and extremely flexible so as to accommodate itself to the relative changes of position of the cars between which it is placed and, at the same time, will be water and dust proof.

The invention has for a further object to provide a vestibule diaphragm so constructed as to resist the lateral displacement of the face plates with respect to each other which tends to take place when the train rounds a curve; my invention, in this respect, providing a construction of the diaphragm whereby such movement or lateral chafing is either prevented or the face plates automatically returned to their normal alignment when the curve has been passed. Because of this feature of the invention it is possible, in some cases, to do away with the use of the springs frequently employed for keeping the diaphragm face plates in proper position with respect to each other.

The invention has for further objects such other new and improved constructions, arrangements and devices relating to metal vestibules for railway cars as will be hereinafter described and claimed.

The invention is illustrated, in a preferred embodiment, in the accompanying drawings, in which—

Figure 1 is a view, in perspective, of a diaphragm constructed in accordance with my invention shown as arranged in the usual manner between the end of the car 55 and a face plate and adapted to bear against it.

the face plate of the diaphragm joining car. Fig. 2 is a section taken on line 2-2 of Fig. 1, showing the diaphragm expanded to its full width. Fig. 3 is a fragmentary drawing illustrating the construction of the diaphragm. Fig. 4 is a diagrammatic section of a pair of co-operating vesti-
bules of the type illustrated in the figures, in the positions which will be assumed when the cars to which they are attached are coupled up or running on a straight track. Fig. 5 is a diagrammatic plan view, partially perspective, illustrating the relative positions of the diaphragms when the cars round a curve so as to bring them into alignment with each other.

Like characters of referred parts in the several figures.

Referring to the drawing, structure is shown as arranged attached to the end wall of the car and a face plate 26. It consists of a plurality of the hollow elements 27, 28, a single walled element 30, ably made of sheet metal. The scopic arrangement one. The widest of the hollow elements 27 is shown as secured to the end wall of the car by screws 31. The front element 27 are formed with flanges 32 which bear against the rear element 28. The elements 28 are formed with corresponding flanges 33 which is narrower than the intermediate element 27 and the members 28 are secured to the inner face, is provided with a flange 34. The element 29 is constructed in the same manner as the element 28 except that it is narrower. The element 30 consists of a sheet of material one edge being bent so as to form a guiding flange 31 other so as to provide a attachment to the face plate 26. The members 37, 38, secured to the end wall of the car and to the face plate 26 are arranged in overlapping relation.

The normal position of the car when the car is coupled up is shown in Fig. 4, the end of the car being designated 25. The positions assumed by

diaphragm when the train rounds a curve, are shown in Fig. 5. By constructing the collapsible elements of the diaphragm of sheet metal and according to the design shown the structure, besides being capable of collapsing on lines longitudinal of the car has sufficient flexibility to permit the collapsing of one side of the diaphragm and the expansion of the other in going around curves and the other distortions made necessary by the relative changes of position as between the ends of the car due to unevenness of the track, banking at curves, and other causes. A vestibule diaphragm must be capable of a certain amount of lateral movement and also a certain amount of vertical movement in order that it may accommodate itself to the oscillatory movements of the car to which it is attached with respect to the adjacent car. The structure above described has this capacity besides being light, strong, slightly in appearance, durable and water and dust proof. Furthermore, as any lateral or vertical movement of the diaphragm face plate puts the structure under stress, with the result that these chafing movements are minimized and the face plate is automatically brought back to proper alignment with the engaging face plate when the forces bringing about the displacements have ceased to act. For this reason it is possible, in many cases, to do away with the springs which are frequently employed on passenger cars to return the face plates to their normal positions after displacement due to chafing.

While I have described my invention as embodied in a preferred construction, it will be understood that modifications might be made in the design, construction and arrangement of the parts without departure from the principles of the invention. Therefore I do not wish to be understood as limiting the invention to the particular constructions, arrangements and devices shown except so far as the claims explicitly contain such limitations.

I claim:

1. A vestibule diaphragm for railway cars comprising a plurality of hollow sheet metal elements having open sides and arranged telescopically one within the other and formed with inturned flanges along said open sides which bear respectively upon opposite sides of the adjacent elements.

2. A vestibule diaphragm for railway cars comprising a plurality of hollow, arched, sheet metal elements having open sides and arranged telescopically one within the other and formed with inturned flanges along said open sides which bear respectively upon opposite sides of the adjacent elements.

3. A vestibule diaphragm for railway cars comprising a plurality of hollow sheet

metal elements having open sides and arranged telescopically one within the other and formed with inturned flanges along said open sides which bear respectively upon opposite sides of the adjacent elements, and an element consisting of a piece of sheet metal which extends into the narrowest of said hollow elements and is formed at its inner end with a guiding bead bearing against opposite sides of said hollow element. 70

4. A vestibule diaphragm for railway cars comprising a plurality of arched hollow sheet metal elements having open sides and arranged telescopically one within the other and formed with inturned flanges 80 along said open sides which bear respectively upon opposite sides of the adjacent elements, and an element consisting of a piece of sheet metal which extends into the narrowest of said hollow elements and is 85 formed at its inner end with a guiding bead bearing against opposite sides of said hollow element. 75

5. A vestibule diaphragm for railway cars comprising a plurality of elements having a sliding engagement one with the other on lines substantially longitudinal of the car and means on each element engaging opposite sides of the adjacent element for preventing said elements from being disengaged one from another when the diaphragm is expanded. 90

6. A vestibule diaphragm for railway cars comprising a plurality of hollow sheet metal elements having open sides and arranged telescopically one within the other, each element being narrower than the internal width of the element into which it projects and being formed with a guiding member bearing against the opposite inner surface of the inclosing element. 100

7. A vestibule diaphragm for railway cars comprising a plurality of arched, hollow, sheet metal elements having open sides and arranged telescopically one within the other, 110 each element being narrower than the internal width of the element into which it projects and being formed with a guiding member bearing against the opposite inner surface of the inclosing element. 115

8. A vestibule diaphragm for railway cars comprising a plurality of hollow sheet metal elements having open sides and arranged telescopically one within the other, each element being narrower than the internal 120 width of the element into which it projects and being formed with a guiding member bearing against the inner surfaces of the inclosing element, the inclosing elements formed, in each case, with oblique flanges 125 which bear upon the sides of the elements inclosed respectively. 125

9. A vestibule diaphragm for railway cars comprising a plurality of arched, hollow sheet metal elements having open sides and 130

arranged telescopically one within the other, each element being narrower than the internal width of the element into which it projects and being formed with a guiding member bearing against the inner surfaces of the inclosing element, the inclosing elements formed, in each case, with oblique flanges which bear upon the sides of the elements inclosed, respectively.

10. A vestibule diaphragm for railway cars comprising a plurality of hollow sheet metal elements having open sides and arranged telescopically one within the other, each element being narrower than the internal width of the element into which it projects and being formed along its inner edges with beads which bear against the inner surfaces of the inclosing element.

11. A vestibule diaphragm for railway cars comprising a plurality of hollow sheet

metal elements having open sides and arranged telescopically one within the other, each element being narrower than the internal width of the element into which it projects and being formed along its inner edges 25 with beads which bear against the inner surfaces of the inclosing element, the inclosing elements being formed with oblique flanges which bear against the outer sides of the elements inclosed therein, respec- 30 tively.

12. A vestibule diaphragm for railway cars, comprising a plurality of arched elements in telescopic engagement and formed to provide throughout the arch four lines 35 of contact between adjacent elements.
